US00D944130S

(12) **United States Design Patent** (10) Patent No.: **US D944,130 S**
(45) Date of Patent: **** Feb. 22, 2022**

(54) **VEHICLE LOWER GRILLE**(71) Applicant: **GM GLOBAL TECHNOLOGY OPERATIONS LLC**, Detroit, MI (US)(72) Inventors: **Gapdong Choi**, Seoul (KR); **Gunjo Hwang**, Incheon (KR)(73) Assignee: **GM Global Technology Operations LLC**, Detroit, MI (US)(***) Term: **15 Years**(21) Appl. No.: **29/709,377**(22) Filed: **Oct. 14, 2019**(30) **Foreign Application Priority Data**

Apr. 29, 2019 (KR) 30-2019-0020263

(51) LOC (13) Cl. **12-16**
